UNITED STATES PATENT OFFICE.

JOHN BLUM, OF DANSVILLE, NEW YORK, ASSIGNOR TO GERTRUDE BLUM,
OF SAME PLACE.

SHOE.

SPECIFICATION forming part of Letters Patent No. 349,562, dated September 21, 1886.

Application filed March 31, 1886. Serial No. 197,246. (No model.)

To all whom it may concern:

Be it known that I, JOHN BLUM, of Dansville, in the county of Livingston and State of New York, have invented certain new and useful Improvements in Shoes; and I do hereby declare the following to be a full, clear, and exact description of the same, reference being had to the accompanying drawings, forming a part of this specification, and to the figures and letters of reference marked thereon.

My invention relates to improvements in shoes, and particularly to that class in which the upper is composed of woven or felted 15 woolen material, fleece-lined and united to a sole of felt or leather, such shoes being particularly adapted for use by those who suffer from cold feet.

The object of my invention is to provide 20 shoes of this class with a sole-leather sole and counter, and to so unite said sole and counter to the upper as to leave the interior of the shoe free from pegs or heavy seams, that would destroy the smoothness and 25 uniformity of the interior of the shoes and offer annoyance to the wearer.

To this end it consists in combining with a 30 woven woolen-top upper, forming a complete casing for the wearer's foot, sole-leather sole and a sole-leather counter united by pegs or stitching to the sole before the application 35 of the woolen upper, and then united to the upper by stitching around the upper edge of said counter, substantially as hereinafter described.

Referring to the accompanying drawings, Figure 1 represents a perspective view of a 40 shoe embodying my invention; Fig. 2, a perspective view of the sole and counter before the application of the upper; Fig. 3, a sectional view taken on the line $x-x$, Fig. 1.

The letter A represents the upper, consisting, preferably, of woven woolen material 45 fleece-lined on the inside and constituting in itself a complete foot-covering. B is the sole, C the heel, and D the counter.

In the manufacture of these shoes the upper is first produced as a finished article. The sole and heel are then cut out and the sole-leather counter cut out and shaped by the 50 usual appliances. The counter and sole are then united by pegs, nails, or stitches, as

preferred, and the heel then pegged on, or the heel, counter, and sole are simultaneously secured by stitching or pegging through them 55 all. After this has been done the upper is applied by stitching through the sole and through the counterpart of the upper from the point s, (shown in Fig. 1,) around to a corresponding point on the opposite side, 60 care being taken that the stitches do not strike through the lining of the upper; after which the counter and upper are connected by applying one or more lines of stitching around the upper edge of the counter, as 65 shown in Fig. 1.

Instead of stitching the sole to the upper first, the counter and upper may be first stitched and the sole and upper afterward. I by preference channel the sole and lay the 70 stitches therein. By this mode of connecting the upper to the sole and counter it will be seen that none of the pegs employed in uniting the sole to the counter and the heel to the sole are struck through the upper, so as to annoy the wearer; but the whole interior of the 75 shoe is left smooth and even, unbroken at any point even by the stitches employed, save that around the upper edge of the counter, which is made with thread of much finer quality 80 than that employed in securing the sole, and produces so light a seam as to be unnoticed in the wearing of the shoe.

The employment of the heavy leather sole 85 imparts a shape and finish to the article, causing it to contrast favorably with shoes of this class, in the construction of which flexible soles of sheep-skin are employed.

Having thus described my invention, what I claim as new is—

The herein-described shoe, consisting of the 90 woolen upper constituting in itself a complete foot-covering, the sole-leather sole united to the upper by stitching, as described, and the sole-leather counter pegged or otherwise attached to the top side of the sole and united to the outside of the upper by stitching around its upper edge, substantially as specified, whereby the entire interior of the shoe is left substantially smooth, as described.

JOHN BLUM.
